ABSTRACT OF THE DISCLOSURE

A squeegee push broom or brush is described which has a bristle-squeegee combination in which the bottom of the squeegee extends beyond the ends of the bottom of the bristles.

This invention relates to a brush construction and more particularly pertains to a push broom which is effective for sweeping dry debris or wet debris.

The brush of this invention is useful for sweeping dry or wet surfaces of floors of various types.

Brushes constructed of suitable material such as canvas or other textile material arranged between stiff, flexible spacing pieces are described in U.S. Pat. No. 756,222. U.S. Pat. No. 106,196 describes brushes composed of two distinct and independent brushes upon the same block, at a wide interval apart, and with a shorter, stiff, intermediate strip placed centrally between them. In the latter brush the stiff central piece is shorter than the bristles so as to allow the bristles to bend and obtain a full sweep of the floor and the central piece is said to only come into action when the bristles are full pressed into the inclined rubbing position of the brush.

The brush of the present invention and certain modifications thereof is more fully described in the accompanying drawings wherein:

FIG. 1 is a side sectional view of the brush.

FIG. 2 is a fragmented front view of the brush partly in section.

FIG. 3 is a fragmented view of the bottom of the brush partly in section.

FIG. 4 is a view in perspective of the brush with threaded handle and slotted squeegee removed.

FIG. 5 is a sectional side view of the assembled components of FIG. 4.

FIG. 6 is a view of another embodiment of elements of the brush including threaded handle and stiffening clip for the squeegee.

FIG. 7 is a side sectional view of the brush assembled from elements shown in FIG. 6.

The brush assembly 1 is made up of an elongated brush block 2 containing tufts of bristles 3 and a flexible squeegee 4 with a handle 5 attached to the top of said brush.

The squeegee sheet 4 is preferably of a tapered cross-section and is provided with an enlarged, triangular, cross-section top edge portion, which is slidably engaged in a dovetail slot 6 running longitudinally of the brush block. In the brush where the handle is connected to the brush block by means of a metal coupling 7 (FIG. 1), the squeegee sheet 4 is tacked into the dovetail slot 6 with metal tacks 8, while in the one brush where the handle is screwed into the brush block (FIGS. 4 and 5), the squeegee sheet is provided with a notch 9 in its upper edge into which the inner end of the handle 5 protrudes to lock the squeegee sheet from longitudinal movement in the block. In this latter form the squeegee sheet does not have to be tacked in place. In FIGS. 6 and 7 is shown another embodiment of the squeegee brush in which the squeegee sheet is first mounted in a rigid clip 10 having a channel

2

cross-section which can be metal or a plastic extrusion of a rigid material. The clip and squeegee then can be forced through the dovetail slot 6. The added rigidity of the clip 10 which squeegies firmly onto the squeegee permits a tight enough fit so that no other means are needed to hold the squeegee in the broom.

In a specific embodiment of this invention the broom or brush 1 is essentially a conventional one with the addition of a flexible squeegee 4 running through the longitudinal center of the mass of bristles 3. In a preferred embodiment the squeegee lower edge projects from the plane of the bristle ends by about $\frac{1}{16}$ inch. In use the squeegee 4 is pressed back against, and is supported by, the mass of bristles 3 behind it. Since the squeegee is in the middle of the broom, it will function on either a push-stroke or a pull-stroke of the broom. The broom is very useful for sweeping dry or wet debris over a smooth or rough floor, efficiently pressing the liquid and dirt before it.

20 ' We claim:

1. A squeegee brush effective for sweeping dry or wet debris comprising

- (a) an elongated brush block having a top and bottom portion,
- (b) a handle demountedly attached near the center top portion of (a),
- (c) a plurality of tufts of bristles attached to and extending downwardly from the bottom portion of (a),
- (d) a flexible squeegee member attached near the center of and extending downwardly from the bottom portion of (a) and running longitudinally for substantially the entire length of (a), the bottom edge of said squeegee extending below the lower end of (c) said squeegee member being of a tapered cross-section and provided with an enlarged, triangular cross-section top edge portion which is slidably engaged in a dovetail slot in and running longitudinally of the bottom portion of (a).

2. A squeegee brush effective for sweeping dry or wet debris comprising

- (a) an elongated brush block having a top and bottom portion,
- (b) a handle demountedly attached near the center top portion of (a),
- (c) a plurality of tufts of bristles attached to and extending downwardly from the bottom portion of (a),
- (d) a flexible squeegee member attached near the center of and extending downwardly from the bottom portion of (a) and running longitudinally for substantially the entire length of (a), the bottom edge of said squeegee extending below the lower end of (c) said squeegee member being of a tapered cross-section and provided with an enlarged, triangular cross-section top edge portion bearing a notch near the center thereof said top edge portion being slidably engaged in a dovetail slot in and running longitudinally of the bottom portion of (a).

3. A squeegee brush effective for sweeping dry or wet debris comprising

- (a) an elongated brush block having a top and bottom portion,
- (b) a handle demountedly attached near the center top portion of (a),
- (c) a plurality of tufts of bristles attached to and extending downwardly from the bottom portion of (a),
- (d) a flexible squeegee member attached near the center of and extending downwardly from the bottom portion of (a) and running longitudinally for substantially the entire length of (a), the bottom edge

of said squeegee extending below the lower end of
(c) said squeegee member being of a tapered cross-
section and provided with an enlarged, triangular
cross-section top edge portion which is mounted in a
rigid clip having a channel cross-section and is slid-
ably engaged in a dovetail slot in and running lon-
gitudinally of the bottom portion of (a).
